UNITED STATES PATENT OFFICE.

JAMES H. CLARK, OF WASHINGTON, DISTRICT OF COLUMBIA, ASSIGNOR OF ONE-HALF
TO JOHN F. KLEAVER, OF WASHINGTON, DISTRICT OF COLUMBIA.

CLOSURE FOR POCKETS.

1,310,282.

Specification of Letters Patent.

Patented July 15, 1919.

Application filed March 10, 1919. Serial No. 281,777.

To all whom it may concern:

Be it known that I, JAMES H. CLARK, a citizen of the United States, and a resident of Washington, in the District of Columbia, **5** have invented certain new and useful Improvements in Closures for Pockets; and I do hereby declare the following to be a full, clear, and exact description of the invention, such as will enable others skilled in the art **10** to which it appertains to make and use the same.

This invention relates to an improvement in closures for pockets, and it consists in a flap secured at one edge to the inner face of **15** one member of the pocket and provided with a button hole for attachment to a button secured to the other member of the pocket near the top, the said flap being stiffened by a reinforcement near its free end and of a **20** length sufficient to form a shallow pocket within the main pocket when attached at its free end to said button.

It further consists in a flap or false pocket, the latter adapted to be closed by passing **25** the button which holds the free end of the flap in place, through a button hole in the member of the pocket to which the flap is permanently secured.

In the accompanying drawings; Figure 1 **30** is a view in perspective of a part of a garment having a pocket therein the view being taken through the pocket; Fig. 2 is a similar view showing the flap in position and forming a false pocket; Fig. 3 is a similar view showing the false pocket closed at **35** its top; Fig. 4 is a view of the flap detached, and Fig. 5 is a view showing the relative positions of the button holes.

6 represents a part of a garment, and for **40** the purpose of illustration only, will refer to it as an overcoat. 7 is the lining and 8 an inside pocket attached to the garment and lining in the usual manner. 9 is a flap made of any suitable flexible material, preferably **45** as wide as the pocket and secured at one edge to the lining adjacent the mouth or opening of the pocket, by stitching or otherwise. The opposite or free end 10 of the flap is provided with a stiffening strip 11 extending throughout the width of the flap for holding the said edge against the inner face of the garment 6 and for preventing the ends of the flap from sagging when the free end of the flap is buttoned. The flap is provided adjacent its free end with a button **50**

hole 12 which preferably extends lengthwise the width of the flap, and is adapted to receive the button 13 which is secured within the pocket near the top of the latter, and when the flap is buttoned thereto as shown **60** in Fig. 2, it forms a false, shallow pocket within the main pocket and prevents entry into the main pocket while it is in its closed or normal position.

To further secure the main pocket against **65** entry, I provide a button hole 14 in the member of the pocket to which the flap is secured and in line with the button 13 so that by first attaching the free end of the flap to the button and then passing the button through the button hole 14, in the opposite side of the pocket the latter will be secured against entry except by the release of the flap, and by making button hole 14 at right angles or at an angle to the button **70** hole in the free end of the flap, it will be impossible to release the flap by a straight or a single pull on the upper end of the lining. It will require one action of the hand to disengage the button from lining 7 and another **75** to disengage the free end of the flap from the button, which could hardly be done without discovery. Even if the garment were hanging up, considerable time would necessarily be consumed in discovering the way **80** to get into the pocket, thus minimizing the danger of loss when the garment is not in use. If the flap should be freed and pushed down it would cover the contents of the pocket and in this way assist in foiling attempts to pick the pocket.

While I have described the improvement as applied to pockets of garments, it is evident that it would be equally applicable to pocket books, hand bags, etc.

Having fully described my invention what I claim as new and desire to secure by Letters-Patent, is:—

1. The combination of a pocket, a flexible flap secured at one end to one edge of the **100** pocket within the latter, and provided at its other edge with a stiffening strip and a button hole, and a button secured to the opposite edge of the pocket and adapted to be entered in the button hole in the flap and **105** support the latter in looped position within the pocket.

2. The combination of a pocket, a flexible flap secured at one end to one edge of the **110** pocket within the latter, and provided at its

other edge with a stiffening strip and a button hole, the portion of the pocket to which the flap is secured being also provided with a button hole, and a button secured to the 5 opposite side of the pocket and adapted to be passed through the hole in the free end of the flap and also through the hole in the

other side of the pocket, the two button holes being at an angle to each other for the purpose described.

In testimony whereof, I have signed this specification.

JAMES H. CLARK.
